UNITED STATES PATENT OFFICE.

WILLIAM W. EILAND, OF FOWLER, CALIFORNIA.

FOLDING CANOPY-SUPPORT.

Specification of Letters Patent.

Patented Apr. 9, 1918.

1,262,471.

Application filed June 20, 1917. Serial No. 175,921.

To all whom it may concern:

Be it known that I, WILLIAM W. EILAND, a citizen of the United States, residing at Fowler, in the county of Fresno and State 5 of California, have invented new and useful Improvements in Folding Canopy-Supports, of which the following is a specification.

This invention pertains to an improved canopy-holder for supporting a canopy over 10 a bed, cot, or the like. The purposes of the invention are to provide a support of the character described which may readily be attached to and detached from any ordinary article of furniture of the above mentioned 15 class, and which may be dismembered for compact arrangement when not in use. It is also proposed to incorporate the features of lightness and strength, and to furnish improved devices for connecting the constituent parts of the support.

For purposes of illustration I have embodied the invention in the unique construction, combination, and arrangement of parts set forth in the specification and claims, and 20 delineated in the drawings, in which—

Figure 1 represents a side elevation of the canopy as applied to a bed;

Fig. 2 is a top plan view;

Fig. 3 is a fragmentary view of the attaching clamp and adjacent portions of the support as attached to a bed; and

Fig. 4 illustrates in detail, the connecting joints of the parts of the support.

Fig. 5 is a detail in elevation showing the manner of mounting the cross bars on the uprights.

As depicted in the drawings, the canopy is applied to a bed and consists of a frame 1 for sustaining a cover 2 of cloth or other material suitable for protecting an occupant of the bed 3 from insects, sun, wind, rain, or other undesirable conditions, and normally maintained in position by cords or ropes 4, extending longitudinally of the frame at a 40 convenient height, preferably above the edges of the bed, and by transverse supporting rods 5, to which the cords 4 are terminally secured. For support of the rods 5, the inner end of each rod 5 is detachably 45 socketed in a fitting 6 secured to the upper extremity of a standard 7 extending downwardly and having the lower end slidably inserted in a socket 8 provided with jaws 9 adapted for clampingly engaging the bed- 50 frame to sustain the canopy-frame 1. Suitable manually-operable means for tightening

ing the jaws are here shown as bolts 10 connecting the jaws 9 and provided with wing-nuts 11. To resist inward strain on the standards 7, a spreader-bar 12 has each end 60 detachably connected to a respective standard 7, and to further increase the rigidity of the frame 1, brace-rods 13 extending between each rod 5 and the bar 12, having one end inserted in a socket 14 attached toward 65 the outer end of the particular rod 5, and the other end inserted in a socket 15 on a sleeve 15' embracing bar 12, which may conveniently be one-third the length of the bar 12 from the respective extremity. The 70 spreader-bar 12 is preferably constructed in three sections 16, 17 and 18 detachably connected by the sleeves 15 which may be secured to the end sections. For connecting each end of the bar 12 to the respective 75 standard 7, I prefer to use a cap 19, secured on the end of the bar 12 and formed with a slot 20 for receiving an upstanding lug 21 provided on the fitting 6; and having for retention of the lug in the slot, a slidably 80 attached pin 22 adapted to engage an opening 23 provided in the lug 21. To retain the rods 5 and 13 in the sockets 6 and 14 respectively, a pin 24 may be inserted in each rod for engagement with a suitably formed 85 slot 25 provided in the socket to constitute a bayonet-joint; and for convenience in assembling and dismounting the frame, the sockets 14 are swingingly attached to the rods 5.

It is to be understood that the herein described embodiment of my invention is intended merely for purposes of illustration, as I reserve the right to variation and modification within the spirit of the invention 95 as indicated by the scope of the accompanying claims.

Having thus described my invention, what I claim is:—

1. In a frame for a canopy, a plurality of 100 spaced uprights, rods extending transversely thereof at the upper ends of the uprights, a spreader bar formed in sections and extending at an angle to the transverse rods and the uprights, means for detachably 105 connecting the spreader bar and uprights, and sleeves for detachably connecting the sections of the spreader bar.

2. In a frame for a canopy, a plurality of 110 uprights and transverse bars mounted at the upper ends of said uprights, a spreader bar formed in sections and extending between

the transverse bars, sleeves connecting the sections of the spreader bar, and braces detachably connected with the sleeves and with the transverse bars.

- 5 3. In a frame for a canopy, a plurality of uprights, cross bars mounted at the upper ends thereof, a spreader bar extending between the cross bars and at an angle thereto, means including a latch member connecting the spreader bar and uprights, sleeves on the spreader bar, and detachable means connecting the sleeves and cross bars.
- 10 4. A cover-supporting device comprising spaced frame elements, flexible cover-supporting means connected to an outer portion of each frame element, rigid means attached to an inner portion of each frame and ex-
- 15

tending between said elements and adapted to restrict relative movement of said elements, and means connected to an outer portion of each frame element and a portion of said rigid means intermediately of said frame elements whereby relative movement of said elements is further restricted.

- 20 5. In a collapsible canopy-support, spaced standards, a spreader-bar connected to said standards, supporting rods connected to said standards transversely of said spreader-bar, flexible supporting means connected to the outer ends of said supporting rods, and brace rods connected to said supporting rods and said spreader bar.
- 25
- 30

In testimony whereof I affix my signature.
WILLIAM W. EILAND.
